CENTRIFUGAL SWITCH

Bernard M. Cain, Marblehead, Mass., assignor to
General Electric Company, a corporation of
New York

Application October 4, 1940, Serial No. 359,728

12 Claims. (Cl. 200—80)

My invention relates to centrifugal switches such, for example, as used in dynamo-electric machines for controlling the circuits of starting windings.

An object of my invention is to provide an improved centrifugal switch which is simple in construction, reliable in operation, and which can be readily manufactured.

Another object of my invention is to provide a centrifugal mechanism with improved structure for operating a stationary switch structure so that rattling of the push collar on the shaft is substantially prevented during the speed range when the stationary switch structure contacts the push collar.

Further objects and advantages of my invention will become apparent from the following description referring to the accompanying drawing, and the features of novelty which characterize my invention will be pointed out with particularity in the claims annexed to and forming a part of this specification.

In the drawing, Fig. 1 is side elevation of an embodiment of my improved centrifugal switch mechanism attached to an end of a rotatable member of a dynamo-electric machine shown in its stationary position; Fig. 2 is a side elevation of the centrifugal switch mechanism illustrated in Fig. 1, the rotatable member having attained running speed; Fig. 3 is an end view in partial section of the centrifugal switch mechanism taken along the line 3—3 of Fig. 1; and Fig. 4 is a side elevation in partial section of the end of the dynamo-electric machine in Fig. 1 showing the centrifugal switch mechanism with the switch member on the stationary part of the machine.

Referring to the drawing, in Fig. 1 I have illustrated a centrifugal operating mechanism attached to an end of a rotatable member 10 of a dynamo-electric machine, which mechanism may be used to actuate a switch which is attached to the stationary member of the machine and is in the starting winding circuit. This centrifugal operating mechanism includes a collar 11 composed of any suitable material such as zinc die casting, and which is movable axially on a shaft 12 of the machine. This collar 11 has an annular shoulder 13 which may abut against an operating lever 14 of the stationary switch designated generally by the numeral 15 in Fig. 4. The collar contacts the lever 14 only when the machine is operating within a predetermined speed range, and above this range the weights move outwardly and the collar moves away from the lever 14. This stationary switch structure may be of any suitable type and, as will be seen as the description proceeds, the operating lever of the switch structure may be designed so as to contact the shoulder 13 substantially at only one point, such as through the buffer 16. The stationary switch structure also includes a contact 17 which is

mounted on the operating arm 14 and a relatively stationary contact 18, the movable operating arm 14 being mounted for movement through a resilient supporting arm 19.

5 In order to operate the push collar 11 so that it will move away from the stationary switch operating lever 14 so that the contacts may open at a certain predetermined speed of the rotatable member 10, outwardly movable weights are provided, which may be of any suitable shape, such as substantially parallel disposed portions 20 connected together by an arm 20a. The weights may be made of any suitable material, such as of a zinc die casting or of a fabricated 10 steel construction. The weights 20 are operatively connected to the push collar 11 through relatively rigid links 21 or by a similar structure. A pair of ribs 22 and 23 is provided on substantially diametrically opposite sides of the push 15 collar 11 in order to support pivot pins 24, so that one end of each of the links 21 may be pivotally connected to the push collar 11. The other ends of the links 21 are pivotally secured to the weights 20 through pivot pins 25 which in turn are supported between pairs of inwardly extending fingers 26 and 27 which extend outwardly from an axially extending portion 28 of the arms 20a of the weights. The weights 20 are movably mounted on the rotatable member 10 through 20 pivot pins 29 which are supported on upstanding portions 30 of a back or supporting plate 31. The supporting plate 31 is rigidly fixed to the rotatable member 10 by screws 32. Any similar mounting would be suitable which would provide 25 the features of this support.

In order to provide a force to oppose the centrifugal force of the outwardly movable weights caused by rotation thereof, a biasing arrangement is provided which includes springs 33 30 which are each supported at one end through an upstanding lug 34 on the back plate 31 and at the other end through an outwardly extending finger 35 on the weights. The springs 33 are designed so that when each 35 is stretched between a lug 34 and a finger 35, the outwardly movable weights 20 will be held in their inward position by a biasing force of a value such that the weights will move outwardly when the rotatable member reaches a predetermined speed. 40 It will be noted that as the weights begin to fly outwardly the links 21 move in a direction such that further movement will increase the force exerted on the collar 11 by the centrifugal force of the weights.

50 In order to prevent rattling of the push collar 11 even though it pushes against an operating lever of the stationary structure at only one point, I arrange the movable weights 20 and the collar 11 so that when the weights are in their inward position as illustrated in Figs. 1 and 3, they will rest against the collar 11. This may be accom-

plished in any suitable manner, and in the illustrated embodiment of my invention I have provided stops on the weights in the form of inwardly extending fingers 36 and cooperating stops on the push collar 11 in the form of ribs 37 which extend between the collar 11 and its shoulder 13. Each of the ribs 37 is provided with an inclined plane surface 38 which cooperates with the adjacent inwardly extending portion 36 of the weight 20 in order that the springs 33 may exert a force on the collar 11 so as to prevent rattling of the collar during the time when the weights are in their inward position. The surface 38 may be inclined any suitable amount with respect to the longitudinal shaft axis so that there is a component of force due to the springs exerted in a direction in line with the shaft axis and in a direction perpendicular thereto. Thus, the spring force is absorbed through the collar when the weights are in their inward position. In order substantially to equalize the forces on the push collar 11 from all sides, the rib members 37 are suitably disposed on the collar so that the torques tending to turn the collar in opposite directions about an axis transverse to the shaft axis will be substantially equal. This is obtained by symmetrically disposing the ribs on both sides of a plane passing through the axis of rotation of the shaft 12, and since the weights 20 also are symmetrically disposed on both sides of the shaft, the springs 33 will cause each of the weights to push the collar through the cooperating stops with components of force towards the shaft, and in line with the shaft. Furthermore, each of the weights will tend to pull the collar towards the rotatable member 10 through the levers 21. In this manner even though the push collar is loosely disposed on the shaft 12 so that it may be easily moved thereon in an axial direction, the push collar 11 will not rattle during the time when the rotatable member 10 is coming up to the critical speed at which time the weights will move outwardly. Therefore, the push collar 11 may be acted upon by an unsymmetrical force through the operating lever of the stationary switch mechanism, so long as that force is less than the forces caused by the springs.

When a dynamo electric machine provided with this type centrifugal switch is started the switch and centrifugal operating mechanism is in the position as shown in Figs. 1, 3 and 4 from the time the rotatable member of the machine is stationary until it reaches a predetermined speed. In this position the collar 11 abuts against the buffer 16 of the operating lever 14 and the stationary and movable contacts are held in a closed position in order to complete a circuit through a motor starting winding. When the motor reaches a predetermined speed, however, the starting winding is no longer necessary and so it may be open circuited. At this critical speed, therefore, the weights will begin to move outwardly until they reach the position illustrated in Fig. 2. This movement of the weights will cause the push collar 11 to move axially on the shaft away from the stationary switch structure to an extent such that the switch contacts 17 and 18 will move away from each other. The weights will remain in this outward position until the rotor slows down to a speed such that the force of the springs will cause them to return to their inward position.

In view of the foregoing, it will be seen that I have provided a centrifugal switch which can be readily manufactured and which is operated by

2 a mechanism, which will operate with a minimum of noise. Thus, during a predetermined speed range when the rotatable member 10 is coming up to a critical speed, the collar 11 will be held relatively rigidly between the stops 36 and the links 21 due to the force of the springs 33. Therefore, the push collar 11 will be forced in one direction, that is, towards the rotatable member 10 by the links 21 and will be in turn pushed in a generally opposite direction through the stops 36 and the inclined portion 38 of the ribs 37. In this manner the push collar 11 will be prevented from rattling even though it is being pushed on by an unsymmetrical force due to the one point contact between it and the operating lever of the stationary switch structure 14.

Although I have shown and described a particular embodiment of my invention, I do not desire to be limited to the particular embodiment described, and I intend in the appended claims to cover all modifications which do not depart from the spirit and scope of my invention.

What I claim as new and desire to secure by Letters Patent of the United States is:

1. A centrifugal switch including an axially movable collar, a supporting plate, outwardly movable weights, means for operatively connecting said weights to said collar, means for movably mounting said weights on said supporting plate, resilient means connected to each of said weights and to said supporting plate for resisting outward movement of said weights, stops on said weights, means on said collar for cooperating with said stops so that the biasing force of said resilient means is substantially absorbed through said collar when said weights are in their inward position, and a circuit controlling device arranged to be actuated by said collar.

2. A centrifugal switch including an axially movable collar, a supporting plate, outwardly movable weights, means for operatively connecting said weights to said collar, means for movably mounting said weights on said supporting plate, resilient means connected to each of said weights and to said supporting plate for resisting outward movement of said weights, stops on said weights arranged to strike said collar when said weights are in their inward position, said stops and collar cooperating with said operatively connecting means and said resilient means so as to prevent rattling of said push collar, and a circuit controlling device arranged to be actuated by said collar.

3. A centrifugal switch including an axially movable collar, a supporting plate, outwardly movable weights, means for operatively connecting said weights to said collar, means for movably mounting said weights on said supporting plate, resilient means connected to each of said weights and to said supporting plate for resisting outward movement of said weights, a circuit controlling device having an operating means, said device being arranged to be actuated by said collar through said operating means, said operating means being arranged to abut against said collar so as to produce an unsymmetrical force thereon, and stops on said weights arranged to strike said collar when said weights are in their inward position so that the force of said resilient means substantially prevents rattling of said collar due to the unsymmetrical force thereon.

4. A centrifugal switch including an axially movable collar, a supporting plate, outwardly movable weights, means for operatively connecting said weights to said collar, means for mov-

ably mounting said weights on said supporting plate, resilient means connected to each of said weights and to said supporting plate for resisting outward movement of said weights, stop means on said collar symmetrically disposed on both sides of a plane passing through the axis of rotation of said collar, stops on said weights arranged to strike said stop means when said weights are in their inward position, and a circuit controlling device arranged to be actuated by said collar.

5. A centrifugal switch including an axially movable collar, a supporting plate, outwardly movable weights, means for operatively connecting said weights to said collar, means for movably mounting said weights on said supporting plate, resilient means connected to each of said weights and to said supporting plate for resisting outward movement of said weights, means on said weights for striking said collar so that said biasing means exerts a force on said weights in a general direction opposite to that force exerted on said weights through said operatively connecting means, and a circuit controlling device arranged to be actuated by said collar.

6. A centrifugal switch including an axially movable collar, a supporting plate, outwardly movable weights, substantially rigid means pivotally mounted on said weights and said collar for connecting said weights to said collar, means for movably mounting said weights on said supporting plate, resilient means connected to each of said weights and to said supporting plate for resisting outward movement of said weights, means on said weights for striking said collar when said weights are in their inward position so as to exert a force in a direction substantially opposite to the force exerted on said collar through said rigid means, and a circuit controlling device arranged to be actuated by said collar.

7. A centrifugal switch including an axially movable collar, a supporting plate, outwardly movable weights, substantially rigid means pivotally mounted on said weights and said collar for connecting said weights to said collar, means for movably mounting said weights on said supporting plate, resilient means operatively connected to said weights and to said supporting plate for resisting outward movement of said weights, ribs on said collar symmetrically disposed on both sides of a plane passing through the axis of rotation of said collar, stops on said weights arranged to strike said ribs when said weights are in their inward position, and a circuit controlling device arranged to be actuated by said collar.

8. A centrifugal switch including an axially movable collar, a supporting plate, outwardly movable weights, substantially rigid means pivotally mounted on said weights and said collar for connecting said weights to said collar, means for movably mounting said weights on said supporting plate, resilient means operatively connected to said weights and to said supporting plate for resisting outward movement of said weights, a circuit controlling device having an operating means, said device being arranged to be actuated by said collar through said operating means, said operating means being arranged to 70 abut against said collar at a point near the outer periphery of said collar, and means on said weights for striking said collar when said weights are in their inward position so that said resilient means substantially prevents rattling of said col-

lar when said operating means abuts against said collar.

9. A centrifugal switch including an axially movable collar, a supporting plate, outwardly movable weights, substantially rigid means pivotally mounted on said weights and said collar for connecting said weights to said collar, means for movably mounting said weights on said supporting plate, resilient means operatively connected to said weights and to said supporting plate for resisting outward movement of said weights, a circuit controlling device having an operating means, said device being arranged to be actuated by said collar through said operating means, said operating means being arranged to abut against said collar at a point near the outer periphery of said collar, ribs on said collar symmetrically disposed on both sides of a plane passing through the axis of rotation of said collar, and stops on said weights arranged to strike said ribs when said weights are in their inward position so that said resilient means exerts a force on said weights in a direction substantially opposite to that force exerted on said weights through said rigid means in order to prevent rattling of said collar.

10. A centrifugal mechanism including a rotatable body, a collar mounted thereon for axial movement, outwardly movable weights, means for operatively connecting said weights to said collar, means for pivotally mounting said weights on said body, resilient means connected to each of said weights and to said body for resisting outward movement of said weights, stops on said weights, and means on said collar for cooperating with said stops so that the biasing force of said springs is substantially absorbed through said collar when said weights are in their inward position in order to prevent rattling of said collar on said shaft.

11. A centrifugal mechanism including a rotatable shaft, a collar concentric therewith and mounted for axial movement, outwardly movable weights, substantially rigid means pivotally connected to said weights and to said collar, means for pivotally mounting said weights on said shaft, resilient means operatively connected to said weights and to said shaft for resisting outward movement of said weights, stops on said weights, and inclined plane means on said collar for abutting against said stops when said weights are in their inward position so that said resilient means tends to force said collar toward said shaft in order to prevent rattling of said collar on said shaft during a speed range when the centrifugal force of said weights is less than the force exerted on said weights by said resilient means.

12. A centrifugal switch including an axially movable collar, a supporting plate, outwardly movable weights, means for operatively connecting said weights to said collar, means for movably mounting said weights on said supporting plate, resilient means connected to each of said weights and to said supporting plate for resisting outward movement of said weights, a circuit controlling device having an operating means, said device being arranged to be actuated by said collar through said operating means, said operating means being arranged to abut against said collar so as to produce an unsymmetrical force thereon, and means including said resilient means for substantially preventing rattling of said collar due to said unsymmetrical force when said weights are in their inward position.

BERNARD M. CAIN.
